REFRIGERATING APPARATUS

Edmund F. Schweller, Dayton, Ohio, assignor,
by mesne assignments, to General Motors Cor-
poration, a corporation of Delaware

Application November 26, 1932, Serial No. 644,473

11 Claims. (Cl. 220—9)

This invention relates to refrigerating appa-
ratus and more particularly to refrigerator cabinets.

As a general rule refrigerator cabinets have
been built with a heavy wooden framework to
which is fastened inner metal walls and on the
outside of which is fastened outer metal panels.
Between the walls there has been provided insula-
tion, such as cork, which has been sealed by
dipping in or covering it with hot asphalt to pre-
vent the access of moisture thereto. Such cabi-
nets have been open to a number of objections in
that they are rather heavy, that they require a
large amount of labor and that they are relatively
high in cost.

The objects of my invention include the pro-
vision of a refrigerator cabinet in which the outer
metal walls form the main structural framework
of the cabinet and which outer metal walls are
sealed so as to prevent the access of moisture to
the insulation, to the provision of a door for such
cabinet which is also frameless and which has
its metal walls forming the main structural
framework of the door, and to the provision of a
simple and unique way of supporting the refrig-
erating apparatus and connecting different por-
tions thereof through the walls of the cabinet.

It is another object of the invention to provide
an improved method of installing and removing
the refrigerating system from the cabinet.

Further objects and advantages of the present
invention will be apparent from the following
description, reference being had to the accom-
panying drawings, wherein a preferred form of
the present invention is clearly shown.

In the drawings:

Fig. 1 is a side vertical sectional view of a re-
frigerator cabinet embodying my invention;

Fig. 2 is a front vertical sectional view of the
cabinet shown in Fig. 1;

Fig. 3 is a transverse sectional view along the
line 3—3 of Fig. 2;

Fig. 4 is a fragmentary transverse sectional
view of the door for the cabinet;

Fig. 5 is a vertical sectional view of the modified
form of the invention in which the refrigerant
compressor is placed beneath the food compart-
ment;

Fig. 6 is a fragmentary transverse sectional
view of a modified form of the door;

Fig. 7 is a fragmentary section of a further
modification of the door; and

Fig. 8 is a section upon the line 8—8 of Fig. 7
with the rubber gasket member omitted.

Referring to the drawings and more particu-

larly to Fig. 1 there is shown a refrigerator cabi-
net 20 which is constructed of a one piece vertical
generally tubular sheet metal shell 21 rectangu-
lar in cross section. In order to hold the tubular
sheet metal shell 21 in position and make it more
rigid, there is provided a rectangular bottom
sheet 22 and a rectangular top sheet 23 each of
which are provided with flanges 24 and 25 which
are fitted within the tubular sheet metal outer
shell with their flanges extending upwardly and
downwardly so as to form the top and bottom enclo-
sures for the outer walls of the food compart-
ment 26 which is located within the outer wall of
the cabinet. The top and bottom metal sheets
22 and 23 have their flanges 24 and 25 tightly
welded to the tubular member so as to form a
hermetic air tight joint. These top and bottom
members strengthen the outer tubular shell so as
to make it self sustaining.

Beneath the bottom sheet metal member 22
there are provided legs 27 at the corners of the
cabinet for supporting the food compartment at
a suitable height above the floor. In the front
portion of the outer tubular sheet metal member
21 there is provided a large opening which is
surrounded by a flange 28. Surrounding the
flange 28 are placed wooden frame members
which form a door jamb frame 29.

In order to properly insulate the walls of the
cabinet there is provided insulating panels one in
each wall of the cabinet. In the bottom wall of
the cabinet there has been provided an insulated
panel 30, in the rear wall, a panel 31, in the top
wall, a panel 32, and in the side walls the panels
33 and 34. These insulation panels are prefer-
ably placed in the cabinet while the cabinet is
lying upon its back. Taking the bottom panel 30
as an example, these panels are made of a plu-
rality of rectangular frames 36 which are made
of some low conducting material such as wood. 40
These frames 36 have sheets of bright metallic
foil 37 stretched thereon and fastened thereto by
a suitable adhesive. After the foil is applied, the
frames are stacked together and fastened together
to form an insulation panel wherein the sheets 45
of bright metallic foil 37 are held in spaced rela-
tion with air spaces 38 in between. On each of
the outer sides of each of the panels there is pro-
vided a sheet of waterproof paper 39.

After the cabinet has been placed upon its back 50
and the insulation panels inserted in their places
in the cabinet it is ready for the insertion of the
inner liner and door molding. It has formerly
been the practice to fasten the inner liner which
is the inner sheet metal wall on the food compart-

ment by having its front edges nailed or otherwise secured directly to the door jamb frame. In order to provide a better insulated cabinet and to facilitate the assembly thereof I have fastened the rectangular door molding 40, which is made of some suitable low conducting material such as wood, to the inner liner 41 which forms the inner sheet metal walls of the cabinet. This inner liner has a flange 42 at its front edge which 5 fits against the rear edge of the rectangular door molding and has a bead which extends over the projecting corner of the door molding. Wood screws extend through the flange 42 into the rectangular door molding to fasten the door jamb molding 40 to the inner liner 41. The door molding 40 in cross section is wedge shaped and has its front end fastened by wood screws to the inner periphery of the door jamb frame 29. The door molding 40 is larger in its outer dimension 10 than the outer dimension of the inner liner 41. Likewise the door jamb frame 29 is also larger than the outer dimension of the inner liner 41. By constructing the cabinet in this manner the assembly consisting of the inner liner and door 15 molding may be slipped into the door opening and fastened from the outside. By this type of construction a substantial barrier is placed between the inner liner 41 and the outer metal walls 29 to prevent heat transfer from the outer walls to 20 the inner walls. In order for heat to travel from the outer wall to the inner liner it is necessary that this heat be conducted through the door molding. Inasmuch as the door molding 40 does not readily conduct heat very little heat will be 25 transferred to the inner liner through this path. This construction greatly facilitates the assembly 30 of the cabinet.

In the upper portion of the cabinet above the food compartment 26 I provide a machinery compartment 44. The machinery compartment 44 has a removable top ornamental cover 45 provided with turned down flanges which fit over the outside of the outer metal walls 21. Within the machinery compartment 44 there is provided 40 a refrigerant compressor 46, preferably of the sealed unit type, which is mounted upon four vibration absorbing brackets 47. These brackets 47 have feet which rest upon the top sheet metal member 23 which is provided with radial ribs 48 formed therein for strengthening this top sheet metal member so that it may support the weight 45 of the compressor unit 46 without being distorted. Beneath the top sheet metal member and directly beneath the feet of the bracket 47 there is provided 50 four bushings 48 of a suitable insulating material such as hard rubber or a phenol condensation product. These bushings 48 are provided with reduced portions and shoulders at their upper and lower ends which extend through 55 suitably located apertures in the top sheet metal member or plate 23 and inner sheet metal member or plate 49 which forms the top wall of the inner liner 41. The reduced portion at one or even both ends of these bushings may be made 60 of a polygonal or irregular shape and the apertures provided with a similar shape so that the bushings will not turn. The refrigerant compressor 46 is fastened to these bushings by having 65 the cap screws 50 extending through the feet of the bracket 47 and threaded into the bushings 48. A refrigerant evaporator 51 is provided in the upper portion of the food compartment 26 immediately beneath the inner sheet metal member 49. 70

75 This evaporator is supported in proper position by

the cap screws 52 which are threaded into the lower end of the insulated bushings 48.

In order to provide a passage through the insulation for the accommodation of the insulating bushings 48 a plurality of transverse flat wooden 5 straps 53, of the same thickness as the framework of the insulation panel 32, are provided between the foil at the proper location and an aperture made through this point of the panel so as to prevent the air spaces between the sheets of foil 10 from being exposed. A passage 54 extending through another set of transverse strips is provided for the refrigerant lines 55 which extend to the evaporator 51. In order to keep these lines out of contact with the outer walls of the passage 15 through the insulation and to close the ends of the passage there is provided rubber stoppers 56 with suitable apertures to receive refrigerant conduits and fitted in the ends of the passage 54 through upper sheet metal member or top plate 23 20 and the inner sheet metal member 49 which may also be called bottom plate. In order to insulate the passage 54 some suitable low insulation such as kapok or mineral wool may be placed therein. The top wall of the cabinet is made removable 25 so that the evaporator and compressor, which are fastened thereto by the bushings 48, may be removed therefrom without disturbing the refrigerating system. This is done by connecting the top plate 23 to the flanges 25 through the medium 30 of the machine screws 57 and a gasket 58 of sponge rubber which is clamped tightly between the edges of the top plate 23 and the flange 25 to make an hermetic seal. A bottom plate or inner sheet metal member 49 is sealed to the 35 inner liner 41 by a suitable sponge rubber gasket 59. This bottom plate 49 has no other support than the bushings 48. The gasket 59 is compressed by the weight of the refrigerating elements upon the panel or top wall and by the 4 clamping action of the machine screws 57. Connected to the compressor 46 and the evaporator 51 by the flexible refrigerant conduits 56 and 78 is a sheet metal plate type condenser 60 which is fastened to the rear wall of the cabinet and which is cooled by vertically flowing air.

A door 61 is provided in the door opening of the cabinet. The rear portion of the door (see Fig. 4) is provided with a deep pan-shaped sheet metal member 62 having flanged edges 63 which are fastened to wooden connecting strips 64 by suitable wood screws 69. The front portion of the door 61 is provided with a flat sheet metal member 65 which has its edges 66 curled over the outer edges of the connecting strips 64 but spaced and insulated from the rear of the sheet metal panel 63. The connecting strips are fastened by means of the machine screws 67 to a bracket member 68 which is preferably spot welded to the sheet metal member 65. At the rear of the connecting strip 64 there is provided a rubber air seal which has a forked end portion with one of the forks 71 fastened beneath the flange 63 of the pan member 62 while the other fork 72 extends over and covers the flange portion 63 of the pan 62 and thereby covers the wood screws 69. A suitable foil insulation panel 73 which is similar to a foil insulation panel heretofore described is provided at the front and rear sheet metal members of the door. The only difference between this panel and the other panels heretofore described is that the door panel is thicker and has an additional sheet of bright metallic foil 74, an additional frame portion and an additional air space providing bet

ter insulation for the door portion of the cabinet.

In Fig. 5, the cabinet has been so modified so as to provide a place for the sealed motor-compressor unit at the bottom. This cabinet 80 is also provided with a vertical generally tubular sheet metal member 81 which has upper and lower transverse sheet metal members 82 and 83 provided with flanges fastened and sealed to the vertical tubular member by a suitable welding or soldering operation. This cabinet is provided with a similar construction in which the inner lining 84 is fastened to the door molding 85 which in turn is fastened to the wooden strips 86 which make up the door jamb frame 86. Beneath the food compartment 87 there is provided a machinery compartment 88. At the bottom of the machinery compartment 88 there is provided an angle iron member 89 which extends around the bottom of the vertical tubular member 81. At the corners of the angle iron member 89 are provided suitable cabinet legs 90 preferably of sheet metal. Extending across angle iron frame member 89 is a small channel member 91. The sealed motor compressor unit 92 is mounted upon vibration absorbing brackets 93 which are fastened to a sheet metal plate 94 which has a forked front end 95 which engages the channel member 91. The rear end of the sheet metal plate 94 is fastened by suitable bolts to a rear cross member 96. The sheet metal plate 94 is fastened by suitable gussets 97 to a vertical plate type condenser 98 which is mounted upon a rear wall of the cabinet. Flexible refrigerant lines 103 from the sealed motor-compressor unit 92 and the condenser 98 extend up the back of the cabinet and over the top of the food compartment 87 through a notch 99 in the front top portion of the cabinet to an evaporator 100 which is supported by the bolts 101 from the bottom sheet metal plate on the top wall of the cabinet. The notch 99 is formed by displacing the central portion of the front sheet metal wall of the cabinet and by cutting a notch in the upper portion of the door jamb 85. Within this notch a suitable rubber tubular member 111 and the refrigerant lines are placed. In order to cover this rubber tubular member 111 and the notch a name plate 102 has been fastened to the cabinet in such a manner as to cover this notch. In this way it is not necessary to pierce any of the insulation panels or the sheet metal walls of the food compartment in order that the refrigerant lines may be connected to the evaporator.

This cabinet is assembled in a manner similar to that described for a top unit style. In the style of cabinet shown in Fig. 5, the vertical generally tubular sheet metal outer shell is first formed into shape and the top and bottom flanged sheet metal members or plates 82 and 83 are then hermetically fastened thereto by a suitable welding or soldering operation. At this time the lower angle iron flange 89 is also welded to the tubular member. The cabinet is then turned upon its back. The insulation panels 105 are placed within the cabinet against the outer sheet metal walls of the cabinet. These panels are made in a manner similar to that described for the top unit style and are composed of a plurality of sheets of bright metal foil spaced by thin air spaces. The rear insulation panel covers the entire rear portion of the cabinet and extends from the top sheet metal member 82 to the bottom sheet metal member 83 and from

one outer side wall to the other side wall. On top of this insulation panel the top and bottom insulation panels, as well as the side insulation panels are placed. At this time the wooden strips which make up the door jamb frame 86 are put into place. The inner liner member 84 and the wedge-shaped rectangular door molding are assembled separately and a reinforcing plate 106 and the evaporator bolts 101 are put into place in the top portion thereof. After making this assembly, the inner liner together with the door molding are slipped into place and the door molding fastened to the door jamb frame by the wood screws 107. By so fastening the door molding to the door jamb frame members, the in-turned flange 108 surrounding the door opening is clamped tightly. In this way the inner liner is supported by the door molding from the outer sheet metal walls of the cabinet. The insulation panels are held against the outer walls of the cabinet by the inner liner 84. The door for the cabinet may be put on the cabinet at this time.

The refrigerating system is then placed into the cabinet with the compressor supported on the cross members 94 and 96 and the condenser is then fastened to the rear wall of the cabinet. After this the flexible refrigerant lines 103 with the rubber tubular member 111 thereon are extended over the top of the cabinet and placed within the notch in front of the cabinet while the evaporator is bolted to the upper portion of the inner liner by the bolts 101. After this, the ornamental nameplate 102 is fastened to the front of the cabinet so as to cover the refrigerant lines at the front of the cabinet and the ornamental top cover 109 is put into position on the top of the cabinet so as to cover the refrigerant lines extending over the top of the cabinet.

In Figs. 6 to 8 inclusive a simplified form of door construction is shown for the cabinet shown in Fig. 5. In this construction, a deep pan-shaped rear sheet metal member 115 is provided with a flanged edge portion 116. An insulating panel 117, made up of a plurality of frames 118 having sheets of bright metallic foil 119 therebetween, is placed within the pan-shaped member 115. On top of this is placed the outer sheet metal door member 120 having a curled edge portion 121 and a necked-in or recessed flanged attaching portion 122 which forms a sort of ledge is placed over the pan-shaped member and the insulation. A thick rubber gasket member 123 is provided between the flanged edge 116 of the pan-shaped member 115 and the recessed attaching portion 122 of the outer sheet metal member 120. This rubber gasket member 123 extends entirely around the door and is provided with an integral air sealing portion 124 which extends therefrom and rests against the curled edge portion 121 of the outer sheet metal member 120. The attaching portion 122 is recessed sufficiently to accommodate the thick rubber gasket member 123. This rubber gasket member acts as an insulation between the pan-shaped member 115 and the outer sheet metal member 120.

In order to fasten these parts together, brass screws 125 are provided which extend through the flanged edge portion 116 of the pan-shaped member 115 and are threaded into a tapped extruded portion 126 upon the recessed fastening portion of the outer sheet metal member. In order to cover the brass screws 125 the rubber gasket is made in a sort of a forked design so that a lip or extension 127 of rubber is provided

which extends over the brass screws 125 and the flanged edge portion 116 of the pan-shaped member 115. It will be seen that this door construction consists of only five elements. The insulation panel, the pan-shaped member, the outer sheet metal member, and the fastening screws 125. This greatly simplifies the construction of the door and lowers the cost of the door by providing a very thick rubber gasket member between the pan-shaped sheet metal member and the outer sheet metal member, heat conduction between the inner and outer sheet metal members is effectively prevented. The brass screws are sufficiently small so that heat leak through the screws is not a serious matter.

However, it is possible to prevent heat leak through the brass screws by the construction shown in Figs. 7 and 8. In this construction keyhole slots 130 are cut in the recessed attaching portion 132 of the outer sheet metal member. Within the smaller portion of the keyhole slot there is slidably inserted the nuts 131 of a material having low heat conductivity such as hard rubber which is provided with a squared groove upon its periphery which engages the edges of the narrow portion of the keyhole slot 130 so that the nut 131 is tightly held and prevented from turning. The brass screws 135 are then threaded into these nuts 131 and otherwise the door is similar in every respect to the form shown in Fig. 6.

While the form of embodiment of the invention as herein disclosed constitutes a preferred form, it is to be understood that other forms might be adopted, all coming within the scope of the claims 35 which follow.

What is claimed is as follows:

1. A refrigerator cabinet including an inner liner, a rectangular door molding fastened to the front edges of the inner liner, said door molding being of a material having low heat conductivity, a door jamb frame of a material having low heat conductivity surrounding the front portion of the rectangular door molding, fastening means for fastening the rectangular door molding to the door jamb frame for supporting the inner liner, sheet metal outer walls fastened to and supporting the door jamb frame, and insulating means between the outer metal walls and the inner liner.

2. A refrigerator cabinet including an inner liner, a rectangular door molding fastened to the front edges of the inner liner, said door molding being of a material having low heat conductivity, a door jamb frame of a material having low heat conductivity surrounding the front portion of the rectangular door molding, fastening means for fastening the rectangular door molding to the door jamb frame for supporting the inner liner, a large vertical generally tubular sheet metal member surrounding the inner liner but spaced therefrom and being fastened to the door jamb frame for supporting said frame, and flanged transverse upper and lower sheets inserted within the tubular member and having the flanges fastened to the tubular member for closing the end portions thereof.

3. A refrigerator cabinet including inner and outer metal walls, insulation between the inner and outer walls, said cabinet having a removable wall comprising a top plate and a bottom plate, an insulation panel between the top and bottom plate, said insulation panel comprising a plurality of sheets including at least one of bright metallic foil held in spaced relation with air spaces between by a framework, said top plate being her-

metically but removably sealed to the outer walls, said insulation panel having a plurality of strips between the sheets of foil and an aperture through the strips and sheets of foil for providing a sealed opening through the foil panel.

4. A refrigerator cabinet comprising a box-like structure including an inner liner forming a compartment to be cooled within said cabinet and having an access opening, means surrounding said inner liner for insulating said compartment, and means forming a supporting structure for the liner and said means for insulating said compartment and forming as well the outer finish walls of the cabinet, said second named means having an opening in one side thereof adapted to register with said compartment access opening of the cabinet and comprising an integral continuously extending one-piece sheet metal tubular element extending continuously across the side of the cabinet having the access opening therein and continuously across two adjacent sides and the back of said cabinet.

5. A refrigerator cabinet comprising a box-like structure including an inner liner forming a compartment to be cooled within said cabinet and having an access opening, means surrounding said inner liner for insulating said compartment, means forming a supporting structure for the liner and said means for insulating said compartment and forming as well the outer finish walls of the cabinet, said second named means having an opening in one side thereof adapted to register with said compartment access opening of the cabinet and comprising an integral continuously extending one-piece sheet metal tubular element extending continuously across the side of the cabinet having the access opening therein and continuously across two adjacent sides and the back of said cabinet, and the vertical portions of said sheet metal tubular element extending continuously beyond the means for insulating said compartment and providing a plurality of vertical walls of a second compartment for enclosing a refrigerating machine adapted to be associated with the cabinet.

6. A refrigerator cabinet comprising a box-like structure including an inner liner forming a compartment to be cooled within said cabinet and having an access opening, means surrounding said inner liner for insulating said compartment, means forming a supporting structure for the liner and said means for insulating said compartment and forming as well the outer finish walls of the cabinet, said second named means having an opening in one side thereof adapted to register with said compartment access opening of the cabinet and comprising an integral continuously extending one-piece sheet metal tubular element extending continuously across the side of the cabinet having the access opening therein and continuously across two adjacent sides and the back of said cabinet, and the vertical portions of said sheet metal tubular element extending continuously beyond the means for insulating said compartment and providing at least three impervious vertical walls of a second compartment for enclosing a refrigerating machine adapted to be associated with the cabinet.

7. A refrigerator cabinet comprising a box-like structure including an inner liner forming a compartment to be cooled within said cabinet and having an access opening, means surrounding said inner liner for insulating said compartment, means forming a supporting structure for the liner and said means for insulating said compartment

ment and forming as well the outer finish walls of the cabinet, said second named means having an opening in one side thereof adapted to register with said compartment access opening of the cabinet and comprising an integral continuously extending one-piece sheet metal tubular element extending continuously across the side of the cabinet having the access opening therein and continuously across two adjacent sides and the

10 back of said cabinet, sheet metal closure means extending across the tubular element above and below the said means surrounding said inner liner for insulating said compartment, and said sheet metal closure means being secured to said tubular element in such manner as to form a hermetic seal about said means for insulating said compartment.

8. A refrigerator cabinet comprising a box-like structure including an inner liner forming a compartment to be cooled within said cabinet and having an access opening, means surrounding said inner liner for insulating said compartment, means forming a supporting structure for the liner and said means for insulating said compartment and forming as well the outer finish walls of the cabinet, said second named means having an opening in one side thereof adapted to register with said compartment access opening of the cabinet and comprising an integral continuously 20 extending one-piece sheet metal tubular element extending continuously across the side of the cabinet having the access opening therein and continuously across two adjacent sides and the back of said cabinet, sheet metal closure means 30 extending across the tubular element above and below the said means surrounding said inner liner for insulating said compartment, said sheet metal closure means being secured to said tubular element in such manner as to form a hermetic seal about said means for insulating said compartment, and portions of said sheet metal tubular element extending continuously beyond one of said sheet metal closure means and providing at least three walls of a second compartment for 40 enclosing a refrigerating machine adapted to be associated with the cabinet.

9. A refrigerating apparatus comprising a wall structure adapted to be supported upon a refrigerator cabinet to form a part of an insulated wall of a food storage compartment thereof, said wall structure including spaced apart sheet metal members and insulating material therebetween, said structure having insulating bushings extending between the spaced apart metal members thereof, a refrigerant circulating means mounted on one side of said wall structure for disposition exteriorly of the food compartment of the refrigerator cabinet, a cooling element mounted on the opposite side of said wall structure for disposition within the food compartment of the refrigerator cabinet, means for securing a por-

tion of said refrigerant circulating means to said bushings, means for securing a portion of said cooling element to said bushings, said securing means cooperating with one another and with said wall structure to form a rigid unitary construction, and said rigid unitary construction being adapted to be bodily removable from the refrigerator cabinet. 5

10. A refrigerating apparatus comprising a wall structure adapted to be supported upon a refrigerator cabinet to form a part of an insulated top wall of a food storage compartment thereof, said wall structure including spaced apart outer and inner sheet metal members and insulating material therebetween, said wall structure having 15 insulating bushings passing through the insulating material thereof and extending between said outer and inner sheet metal members, a refrigerant circulating unit mounted on the side of said wall structure adjacent said outer sheet metal 20 member thereof for disposition exteriorly of the food compartment of the refrigerator cabinet, a cooling element mounted on the side of said wall structure adjacent said inner sheet metal member thereof for disposition within the food compartment 25 of the refrigerator cabinet, means for securing a portion of said refrigerant circulating unit to said bushings, means for securing a portion of said cooling element to said bushings, said securing means cooperating with one another and 30 with said wall structure to form a rigid unitary construction, and said rigid unitary construction being adapted to be bodily removable from the refrigerator cabinet.

11. A refrigerating apparatus comprising a wall structure adapted to be supported by a refrigerator cabinet to form a part of an insulated wall of a food storage compartment thereof, said wall structure including spaced apart metal members and insulating material therebetween, said structure having insulating bushings extending between the spaced apart metal members thereof, a closed refrigerating system attached to said wall structure and including an evaporator connected with a plurality of elements forming a refrigerant liquefying and circulating unit, means for securing a portion of said evaporator to said bushings on one side of said wall structure for disposition within said food storage compartment of said cabinet, means for securing a portion of 40 one of said elements of said refrigerant liquefying and circulating unit to said bushings on the opposite side of said wall structure for disposition exteriorly of said food storage compartment, said securing means cooperating with one another and 45 with said wall structure to form a rigid unitary construction, and said unitary construction being adapted to be bodily removable from the refrigerator cabinet. 50

EDMUND F. SCHWELLER. 60
